UNITED STATES PATENT OFFICE.

FRANCIS M. HENSHAW, OF OKLAHOMA, OKLAHOMA.

GRINDING DEVICE.

1,240,716.

Specification of Letters Patent. Patented Sept. 18, 1917.

Application filed October 6, 1916. Serial No. 124,068.

To all whom it may concern:

Be it known that I, FRANCIS M. HENSHAW, a citizen of the United States, residing at Oklahoma city, in the county of Oklahoma 5 and State of Oklahoma, have invented a certain new and useful Improvement in Grinding Devices, of which the following is a specification.

My invention relates to improvements in 10 grinding devices.

The object of my invention is to provide a grinding device adapted for sharpening scissors, knives and other articles which may be economically manufactured, which is 15 simple, strong and durable and not liable to get out of order and which is efficient in its operation.

My invention also provides a construction which may be secured in operative position upon the sewing machine without the employment of any clamps or similar devices for locking the grinding device to the sewing machine, but which after being slid into the operative position on the sewing 25 machine may be retained in such position and operated by frictional contact of a rotating element thereof with the fly wheel of the sewing machine.

The novel features of my invention are 30 hereinafter fully described and claimed.

In the accompanying drawing which illustrates the preferred embodiment of my invention,

Figure 1 is a side elevation of my improved 35 grinding device.

Fig. 2 is a plan view of the same.

Fig. 3 is a side elevation showing my improved grinding device in operative position upon a sewing machine, the upper portion 40 of which is shown, the support of the grinding device being retained in position by means of a spring connecting the support with an anchor attached to the table of the sewing machine.

Fig. 4 is a perspective view of a crank 45 adapted to be attached to the shaft of the grinding device for manually turning the shaft.

Similar reference characters designate 50 similar parts in the different views.

1 designates a support preferably in the form of a tripod provided with three vertical screw-threaded holes in which are fitted respectively three screws 2 which are 55 vertically adjustable and form feet for supporting the device upon the table 3 of a

sewing machine of the ordinary household type.

The lower ends of the screws 2 are preferably provided with rubber tips 4 which 60 serve the function of a resilient bearing and also for the prevention of marring the surface of the table, 3.

Rotatably carried on the support is a grinding member such as an emery wheel 5 65 which may be used for grinding or sharpening articles of various kinds.

Operatively engaging the wheel 5 is a frictional driving means preferably comprising a horizontal shaft 6 located intermediate of the screws 2 having secured to it a friction pulley 7, preferably having an annular grooved periphery adapted to engage and be rotated by the fly wheel 8 of the 75 sewing machine.

Preferably the pulley 7 engages the under side of the fly wheel 8 at a point intermediate of the right and left hand screws as viewed in Fig. 3, whereby the pressure between wheels 7 and 8 required to rotate 80 the pulley 7 and the shaft 6 and grinding wheel 5, will not tend to laterally tip the grinding device on the table 3. This location of the point of contact intermediate of the screws and against the under side of 85 the fly wheel 8 also tends to retain the grinding device in the operative position shown in Fig. 3, when the wheel 8 of the machine rotates in a counter-clockwise direction as viewed in Fig. 3. 90

In operating my invention, the screws 2 are adjusted vertically, so as to adapt the machine to any inequalities in the upper side of the table, and also to bring the pulley 7 into operative relationship with the 95 fly wheel 8 regardless of the diameter of the fly wheel or of its height above the table.

After such adjustment has been made of the screws 2, it is but necessary to slide the mechanism horizontally upon the table top 100 into or from the operative position.

When the fly wheel 8 rotates counter-clockwise, as viewed in Fig. 3, no clamps or other securing devices are needed to hold the grinding device operatively engaged 105 with the wheel 8.

In the event that the fly wheel 8 rotates, as it does in some machines, in a clockwise direction, as viewed in Fig. 3, I provide means which exerts force in the horizontal 110 direction tending to hold the pulley 7 engaged with the fly wheel 8.

Such means may comprise a coil spring 9, one end of which is secured to the adjacent screw 2 and the other end of which is affixed to an anchoring device comprising a hook 10 adapted to engage one side edge of the table 3, the tension of the spring 9 being such that it will pull the supporting member 1 and yieldingly hold it in the operative position.

10 It will be obvious that my improved grinding device may have the pulley 7 driven by the belt or other running parts of the sewing machine, or the pulley may be rotated by being connected with an electric or 15 other motor.

In order that the shaft 6 may be rotated by hand, as well as by power, one end of the shaft 6 is provided with a squared portion 11 adapted to slidably fit a square 20 socket 12 provided in a detachable crank 13 shown in Fig. 4.

The disposition of the screws 2 relatively to the shaft 6 is such that stability will be afforded to the grinding mechanism when 25 the latter is in operation.

I do not limit my invention to the structure shown and described, as modifications, within the scope of the appended claims, may be made without departing from the 30 spirit of my invention.

What I claim is:—

1. In combination, a grinding member, a friction pulley, a shaft carrying said mem-

ber and said pulley and a support for the shaft adapted to rest on the top of a sewing machine table and to freely slide thereon and to hold the shaft at an elevation such that the point of contact of the sewing machine fly wheel and friction pulley is slightly above the lowest point of the fly wheel, whereby when the fly wheel is rotated in a direction such that any point on its periphery travels from said point of contact downwardly, the pulley will be maintained by friction in contact with the fly wheel.

2. In combination, a frictional driving means, a grinding member carried thereby, and a support on which said driving means is rotatable, said support being adapted to rest on the top of a sewing machine table and to move freely thereon and to hold the driving means at an elevation such that the point of contact of said driving means and the sewing machine fly wheel is slightly above the lowest point of the fly wheel, whereby when the fly wheel is rotated in a direction such that any point on its periphery travels from said point of contact downwardly, the driving means will be maintained by friction in contact with the fly wheel.

In testimony whereof I have signed my name to this specification.

FRANCIS M. HENSHAW.
